Filed Nov. 24, 1972, Ser. No. 308,982

Term of patent 14 years

Int. Cl. D7—02

U.S. Cl. D7—108

Fig. 1.

Fig. 2.

FIG. 1 is a perspective view disclosing the side and one end of my combined portable smokehouse and bar-b-que grill coupled to the smokehouse. The undisclosed side is a mirror image of the side shown and the undisclosed end is plain except for the foldable table as shown.

FIG. 2 is a perspective view disclosing the side and one end thereof in an alternate position, wherein the bar-b-que grill is mounted on top of the smokehouse, the table is in collapsed position and the coupling element shown in FIG. 1 has been omitted for convenience of illustration.

I claim:

The ornamental design for a combination portable smokehouse and bar-b-que grill, as shown and described.
